ELECTRICAL COMPENSATOR FOR THE DIRECTIONAL TRANSMISSION OR RECEPTION OF WAVE ENERGY

Fritz Alexander Fischer, Kiel, Germany, assignor to Electroacoustic Gesellschaft mit beschränkter Haftung, Kiel, Germany, a firm

Application October 28, 1930, Serial No. 491,740
In Germany November 21, 1929

14 Claims. (Cl. 177—386)

Any arrangement of oscillators in a plane has, as is well-known, a quite definite directional characteristic, the shape of which depends upon the geometrical configuration, the ratio of the distances between the oscillators to the wave-length, and the individual characteristic of the oscillator. This directional characteristic is known as "the natural characteristic" of the oscillator group as distinguished from "the artificial characteristic", which arises when the individual oscillators are given certain time lags. In practice, the simplest way of producing these time lags is by means of retardation lines comprising impedance networks, which uniformly retard all the frequencies of the band which it passes. If it is desired to use oscillator group arrangements for purposes of direction determination, it is necessary, when using the natural characteristic, to rotate the group, which is not possible in most cases, for instance, in subaqueous direction determination. In such cases, fixed group arrangements are used in combination with so-called compensators which contain the artificial lines. The characteristics used for purposes of direction determination usually have a pronounced main maximum, and when determining direction according to the maximum method it is the purpose of the compensator to vary the retardation of the oscillators in such a way that the main maximum rotates simultaneously with the angle of direction determination.

Various arrangements are already known for effecting these variations in retardation, but they either employ several retardation lines or apply only to special oscillator arrangements. The object of the present invention is to provide a compensating arrangement which works with only a single retardation line, and which is applicable to any arrangement of oscillators in space.

According to the present invention, an electrical compensator for the directional transmission or reception of wave energy by means of a group of oscillators is provided, wherein the sections of a retardation line or compensator chain are connected to a corresponding number of insulated contact strips over which sliding contacts, arranged in suitable geometrical configuration and connected with the oscillators are rotated in their configuration. This may be accomplished for instance by arranging the contacts in a geometrical configuration similar to the one in which the configuration of the oscillators appears in the plane in which the wave

energy is propagated, and in which the direction is to be determined. For example, in submarine signalling to other vessels or to shore the wave energy is propagated substantially in a plane which is parallel to the surface of the water and this would be called the plane of transmission or reception, or in short the "plane of wave energy propagation". If now in such a case the oscillators appear in a certain geometrical configuration in that plane of propagation, the compensator contacts should according to the invention be arranged also in a plane and in a configuration, geometrically similar to the oscillator configuration.

The invention will be more clearly understood with reference to the accompanying drawings in which—

Fig. 1 shows the theoretical principle underlying the present invention.

Fig. 2 shows a practical form of construction for carrying the invention into effect, and in which a single retardation line serves for compensating these oscillators.

Fig. 3 shows another form of construction of a compensator according to the invention, in which more than one artificial line cooperates with the sections of the contact strips, and

Fig. 4 shows a compensator according to the invention, partly in vertical section, and designed for a number of oscillators which are arranged upon the surface of a sphere.

Fig. 1 will serve for the explanation of the operation of the compensator and the method of rotating the directional characteristic. Let P be the point which is to be chosen at will and about which the system is to be rotated. This center of rotation would preferably be located within the group of oscillators, so that the circumscribed circle around center P passes through the oscillator furthest away from this center. In the present case let 1 be the one of the three relatively fixed oscillators 1, 2, 3 which is at the greatest distance from P. Let the sound beam Q meet the circle with the radius r₁ around P at K. t is the tangent to this circle at K, and indicates in this diagram the wave front, positioned at right angles to the direction of wave propagation. The perpendiculars V₁, V₂, V₃ from the oscillators to this tangent are obviously an index for the lags which the oscillators must be given in order that, for instance in reception, an impulse which meets the different receivers at different times will be heard in the telephone at the same time. How these lags must alter with the direc-

tion of incidence—when the oscillators are rotated as a group around P—in order that the same effect may be produced for all directions of incidence, can clearly be seen from Fig. 1.

5 A constructional form of the compensator according to the present invention is illustrated in Fig. 2. This construction satisfies the object of the invention in providing a compensator which is applicable to any arrangement of oscillators 10 for directional transmission or reception in a plane and in which only a single chain is employed. Moreover, the compensator illustrated is very simple in construction. The retardation line or chain 4 is connected with its individual sections to contact bars 5 which are assembled to form a flat surface, but are separated from one another by narrow insulating strips 6. The number of bars is equal to the number of chain sections. One end of the chain is connected to the telephone 20 7, if necessary, through an amplifier, or else to a generator (shown in dotted lines) in case of transmission. At the opposite end, the filter is closed by a resistance 8 which is equal to its surge impedance. On these contact surfaces 5 slide contacts 1^a, 2^a, 3^a which are mounted on a contact carrier 9 and are each connected to one pole of one of the individual oscillators 1, 2, 3. The other poles of the oscillators are connected to the common conductor of the chain 4. The connection 25 of the sliding contacts to the oscillators is effected through brushes b₁, b₂, b₃ and slip-rings s₁, s₂, s₃ respectively.

30 As stated with reference to Fig. 1, also in this case the designer takes a given oscillator configuration (resulting for instance from the arrangement of the oscillators on a vessel or on the sea bottom in parallel to the surface of the water) such as shown at 1, 2, 3 in Fig. 2, and circumscribes any convenient size circle around this 35 group, preferably with the center located within the group, so as to be able to get along with the smallest possible circle. In such a case one, possibly several of the oscillators may be located on the periphery of such a circle. Then the designer 40 transposes this configuration in a scale suitable for the size of contact carrier 9 onto this carrier and locates the sliding contacts 1^a, 2^a, 3^a on the corresponding corners of this similar geometrical figure, taking care in the transposition that the 45 contacts have the same relation to the rotation center P of the carrier as the oscillators 1, 2, 3 have to the center P of their circumscribed circle. This is an operation fully within the province of a skilled draftsman. In Fig. 2, purely for convenience of illustration, the circle including the oscillators 1, 2, 3 is much smaller than the circle including the contacts on carrier 9, while in reality of course the reverse prevails. The oscillator circle may in reality for instance be of the order 50 of six feet in diameter and the carrier circle only 1.5 feet. If the oscillators are not all situated in the plane of direction determination but are distributed in space, the arrangement of the sliding contacts should be made in conformity with the 55 projection of the receivers on the plane of direction determination. The use of the geometrical projection of the actual configuration of oscillators, arranged on an irregular surface, into the plane of wave energy propagation, and the use 60 of the geometrical configuration produced thereby as a basis for designing a plane and geometrically similar contact configuration for any kind of compensator, is not the present applicant's invention. This particular idea forms the subject 65 matter of a copending application Serial No.

544,267, Patent No. 1,977,974 by Wilhelm Rudolph, and may be used in the present case in combination with the present applicant's novel strip compensator by which the compensation of oscillators mounted on irregular surfaces and the construction of the compensator is very materially simplified. In the example under consideration, the holder 9 of the sliding contacts is arranged rotatably about P. The area of the contact surface need evidently not be greater than the diameter of the circle which is described by the sliding contact which is at the greatest distance from the point of rotation, in this case r¹.

10 Let us now assume that contact carrier 9 is in the position shown in dotted lines, so that the 15 position of contacts 1^a, 2^a, 3^a and the orientation of their configuration corresponds exactly with that of oscillators 1, 2, 3. Let us assume first that a sound beam strikes the oscillators 1, 2, 3 from the right in the direction of the single 20 feathered arrow a. Then it will be clear that receiver 3 is first encountered by the beam and the two receivers 1 and 2 are encountered later, but simultaneously. If now all three receivers 25 are connected to the same telephone 7 as shown, and if it is desired that the sound impulses arriving at all three receivers should be perceived simultaneously in the telephone in order to there produce a maximum sound, it is obvious that between receiver 3 and the telephone the greatest 30 number of sections of the artificial line must be connected, while between receivers 1 and 2 and the telephone smaller, but equal numbers of chain sections must be connected. This is accomplished by the sliding contact position 1^a, 35 2^a, 3^a in Fig. 2. It will be seen that in this position the receiver line runs from receiver 3 by way of the pertaining brush b₃ and slip ring s₃ to the brush 3^a and thence over the contact strip 5 on which it rests to the sixteenth section of 40 the artificial line. Thus sixteen sections of this line are connected between that receiver and the telephone 7. The lines from receivers 1 and 2 lead respectively by way of brushes 1^a and 2^a to the same contact strip 5 on which they rest and 45 which is connected to the fourth section of the artificial line 4. Thus, between these receivers and the telephone only four line sections are connected. The difference 16—4=12 chain sections 50 corresponds with the sound path from the receiver 3 to the receivers 1 and 2 taken in the direction of the single feathered arrow a.

55 As the second example it is assumed that the sound beam arrives in the direction of the double feathered arrow b. It has been turned by 90° counterclockwise. In this case it will be noted that the sound strikes receiver 1 first, then receiver 2, and last the receiver 3. With the rotation of the sound beam by 90° counterclockwise corresponds a rotation of the contact carrier 9 clockwise by 90°, (in this and the following sound beam position only the contact brushes of the carrier are shown in the different positions without showing the carrier itself turned in order to simplify the illustration). The contact brushes are now in the positions 1^b, 2^b, 3^b. It will be noted that in this position sixteen chain sections have been switched between the receiver 1 and the telephone, and according to the corresponding brush position 2^b twelve chain sections 60 have been connected between the telephone and receiver 2, and in accordance with the position 3^b of the pertaining brush eight chain sections 65 are connected between the receiver 3 and the telephone. These differences in the number of 70 75

chain sections correspond approximately with the relative distances of the receiver 2 from 1, and 3 from 2 measured in the direction of the beam; in other words they are the equivalent of the sound path differences.

If the sound beam rotates further counter-clockwise into the direction indicated by the triple feathered arrow c it will be obvious that now oscillators 1 and 2 are first encountered simultaneously, i. e. they both must be provided with an equal but large number of sections. Oscillator 3 is encountered last, and thus should have only a small retardation. When the sound beam has moved in the last-named position the contact bridge 9 must be turned clockwise by another 90° , so that the brushes now are in the positions 1 $^\circ$, 2 $^\circ$, 3 $^\circ$, i. e. between each of the receivers 1 and 2, and the telephone are now inserted fifteen chain sections, while between the receiver 3 and the telephone only three sections are inserted.

This proves qualitatively that when the sound beam rotates and the contact bridge is rotated accordingly, the number of chain sections switched between the telephone and the respective receivers is always proportional to the relative values of the retardation in the individual receivers, i. e. in all positions which correspond to a maximum in the telephone the correct compensation for the individual receivers in order to bring about the desired retardation is attained.

In order not to obscure the drawings, only comparatively few compensator chain sections, and correspondingly few contact bars 5 are shown in Fig. 2. It will be obvious to the skilled person that the more contact bars with their corresponding chain sections are provided, the more exact will be the observation of the direction. In practice for instance 60 contact bars with their appertaining individual chain sections have been used successfully for directional observations exact within three degrees of the compass circle.

Quantitatively and generally speaking for any retardation value V_x (such as for example in Fig. 1) of any receiver x , the value of

$$V_x = r_1 + r_x \cos. \alpha$$

in case of groups on areas, such as we deal with in Figs. 1 and 2. For instance the value V_3 for the receiver 3 would be derived as follows:

$$V_3 = r_1 + \overline{p_3}$$

$$\overline{p_3} = r_3 \cos. \alpha$$

or

$$V_3 = r_1 + r_3 \cos. \alpha$$

$$V_x = r_1 + r_x \cos. \alpha$$

In these foregoing equations r_1 represents the radius of the largest circle drawn through the outermost receiver of the group (Fig. 1), r_x the radius of the circle drawn through the receiver x under consideration (in this case receiver 3), and $\cos. \alpha$ represents the angle which the sound beam forms with the radius of receiver under consideration. In the accompanying sketch the sound direction is represented by the arrow Q .

The fundamental difference of the compensator according to the present invention compared with compensators used before and its considerable advantage lie in the fact that for widely different arrangements of oscillations one and the same type of compensator may be used and only the position of the sliding contacts in the holder (9

in Fig. 2) has to be chosen according to each individual configuration of oscillators in space. Since it has been found that, especially on board of ships, only very few places exist, in which for instance noise receivers can be mounted with any hope of success (mostly only in the bow of the ship) and since, consequently, it has been necessary to accommodate the respective position of the oscillators to the possibilities of mounting them on board ships, the importance of this invention is evident, because in any other constructions of compensator for each individual distribution of oscillators an individual construction of the whole compensator (including artificial line and contact holder) had to be worked out.

With such single chain compensators, however, drawbacks arise due to the reduction in intensity of the sound arriving at the telephone, caused as will be more fully explained, by reflection and absorption due to the several receivers connected to the chain. A further object of the present invention is to remove or decrease this disadvantage. To this end the contact strips are sub-divided in transverse direction and the groups of strips thus formed are connected to different retardation lines.

Referring to Fig. 3, the three sound receivers are assumed to be arranged similar to Fig. 2, 11 and 20 are the contact strips of the compensator which are separated by insulating strips, 9 is the contact carrier, 1 $^\circ$, 2 $^\circ$, 3 $^\circ$ are the sliding contacts for the receiver lines of the receivers similar to Fig. 2, and 41 to 49 are compensating resistances. The energy supplied in this case from each individual receiver to the compensator chain is weakened partly by reflection and partly by absorption on travelling through the chain to the telephone 23, due to the other receivers which are situated between the receiver under consideration and the telephone. A further consideration of the conditions shows that this sound intensity is directly proportional to the number of receivers. Therefore, if only a definite sound intensity loss through the compensator is permissible the number of receivers is limited, if only one single contact path is employed. If it is desired to use several compensator chains, a special strip contact path must be allotted to each chain and thus a large and expensive compensator is the result.

In order to avoid this drawback the present invention further consists in an arrangement which allows of distributing the receivers with a single contact path simultaneously over several chains. It is conceivable to accomplish this by splitting the single strip compensator transversely to the direction of the strips. By this means, several strip compensators are formed, to each of which a compensator chain is connected. The energy at the telephone is now increased not only due to the fact that fewer receivers run on each chain, but also due to the fact that the individual chains are connected in series.

This beneficial result arises from the following contemplation:

Let us assume that we have a definite number N of receivers. In an article published by me in the Zeitschrift fuer technische Physik XII year No. 6, 1931, pages 292 to 298, I have shown (see page 297) that the voltage E at the end of a compensator chain is inversely proportional to the square root of the number of receivers N , and that the optimum sound intensity L of an adjusted chain is directly proportional to the number of receivers.

Now if all receivers N are connected to one chain, the voltage at the end of the chain is:

$$E_1 = \gamma \cdot \sqrt{N}$$

and thus the sound intensity

$$L_1 = \gamma^2 N$$

If the same number of receivers N is distributed over two chains, the individual voltage at the end of each chain amounts to

$$e = \gamma \cdot \sqrt{\frac{N}{2}}$$

Since both chains are connected in series, the total voltage which is supplied to the telephone amounts to

$$E_2 = 2\gamma \cdot \sqrt{\frac{N}{2}} = \gamma \cdot \sqrt{N} \cdot \sqrt{2}$$

and thus the sound intensity

$$L_2 = 2\gamma^2 N$$

If the same number of receivers N is distributed over three chains, the individual voltage at the end of each chain

$$e = \gamma \cdot \sqrt{\frac{N}{3}}$$

Since all three chains are connected in series, the total voltage supplied to the telephone amounts to

$$E_3 = 3\gamma \cdot \sqrt{\frac{N}{3}} = \gamma \cdot \sqrt{N} \cdot \sqrt{3}$$

and thus the sound intensity

$$L_3 = 3\gamma^2 N$$

Therefore with respect to voltages gained by the sub-division of the compensator we have the relations

$$\frac{E_2}{E_1} = \sqrt{2}$$

respectively

$$\frac{E_3}{E_1} = \sqrt{3}$$

and with respect to sound intensities we have the relations

$$\frac{L_2}{L_1} = 2$$

respectively

$$\frac{L_3}{L_1} = 3$$

The conditions are shown in Fig. 3 for the simplest case of the division of a flat strip compensator into two parts I, II with two compensator chains 21 and 25 connected to them respectively. The course of the dividing line L is optional and is preferably arranged in such a way that, with the desired contact arrangement, on an average approximately the same number of contacts cooperate with each of the compensator halves I and II during the whole revolution of the contact carrier. The chains are closed at one end by ohmic resistances 73 and 74 respectively which are equal to the pertaining compensator surge impedance, whilst transformers 71 and 72 respectively are connected to the other end of the chains. The secondary sides of these transformers are connected in series and connected in such a way that a receiver does not reverse polarity on passing over from one to the other half of the path. 23 is a telephone, 95 an alternating current generator which can be switched in place of the telephone when the arrangement is used

for the emission of a directed sound beam. The strips of the compensator are denoted 11-20, while 41-49 and 81-89 are compensating resistances for the purpose of compensating the variations of the chain resistance corresponding to the varying positions of the sliding contacts. The other reference characters correspond to those in Fig. 2.

The greater the number of oscillators becomes, the more numerous should be the transverse division of the strip compensator, and thus, the greater the increase in the numbers of chains.

Furthermore, the idea of the invention as illustrated in Figs. 2 and 3 for the direction determination in a single plane of transmission is not limited to strip compensators of the illustrated type in which straight parallel strips located in a single plane are used, but may be applicable to strip contact surfaces arranged in a continuous surface of a higher order, so long as the geometric configuration of the contacts sliding over such a contact surface corresponds directly with the configuration of the oscillators or indirectly with the projection of this configuration into the plane of energy transmission.

If direction determination or transmission of energy in space is required, i. e. in three dimensions, the arrangements shown in Figs. 2 and 3 or their modifications do no longer suffice. Such a direction determination requires the arrangement of the oscillators on a spherical surface. Correspondingly the contact strip surface and the contact bridge cooperating therewith must have spherical form.

For example, if one desires to determine the direction of wave energy arising in space (such as the direction of sound from an airplane) an arrangement must be used, such as is shown in Fig. 4, in which the receiving oscillators S_{31} to S_{76} are distributed over the surface 145 of a skeleton sphere, standing elevated above ground as shown. Correspondingly the contact strips of the compensator are arranged in horizontal zones 101 to 125 of a sphere as shown at 220. Similarly to the manner shown in and for the purpose described with reference to Fig. 3, this strip sphere may be divided, if necessary, for instance into two separate halves at right angles to the strip zones along the dividing line L . According to the spherical shape of the contact surface the sliding contacts which are connected to the oscillators S_{31} to S_{76} must be arranged on a spherical carrier as also shown in Fig. 4. As will be seen from this figure, the spherical carrier 140 surrounds the strip sphere 220, which latter is supported at one end 55 of its equatorial axis $a-a$ by a hollow axle 137 fixed on a hollow stanchion 136. The conductors from the individual sections of the two compensators K are united into a cable 92 and conducted through hollow stanchion 136 and hollow axle 137 into the interior of the strip sphere where they are connected respectively to the individual strip zones as shown at 139. The spherical carrier 140 is carried by a shaft 132 journalled at 133 in a semi-circular bail 134 which in turn is journalled at one of its ends on axle 137 and at the other end on axle 91 of stanchion 135. Thus the bail with shaft 132 can in Fig. 4 swing on equatorial axis $a-a$ in a direction at right angles to the sectional plane in which Fig. 4 is shown. In this manner rotation can be imparted to carrier 140 on its polar and on an equatorial axis to make respectively azimuth and elevation adjustments of the carrier. The contacts C_{31} to C_{76} are distributed on the carrier corresponding with the distribution of oscil-

lators S₃₁ to S₇₆ on sphere 145, respective contacts being connected with correspondingly positioned oscillators by way of individual conductors joined into a cable 138. This cable terminates near shaft 132, where the conductors are connected to individual brushes 131 mounted on a brush holder 131^a which is carried by bail 134. These brushes slide on individual insulated slip rings 130 mounted on shaft 132, each ring having a lead (shown in dotted lines) passing through hollow shaft 132 to its appertaining sliding contact on the carrier. In order to permit rotation of the carrier on its polar axis nearly 180° in either direction, an equatorial slot 90, extending nearly around its circumference, is provided in the carrier through which hollow axle 137 extends. When, in making the observation the operator, in adjusting the elevation and azimuth angles until he observes for instance a sound maximum in the telephone 23 (Fig. 4), has found the directional angles in space of the object sought, he may read these two adjusted angles on the device by any suitable means known in the art, and not shown here, by reading the degrees by which the two axes have been shifted from an assumed normal position.

Instead of moving the sliding contacts, they may also be arranged stationary and the contact strips may be movable with regard to them.

Of course, the invention is not limited to the reception of sound waves or other waves or impulses, but can also be used with the same advantage for the transmission of such waves where, of course, instead of the measuring or registering apparatus (for instance, the telephone illustrated) a wave or impulse generator, for example, an alternating current generator 95, must be used. By waves or impulses are also meant electromagnetic waves and, generally speaking, all types of energy in wave form.

40 I claim:—

1. An electric compensator for a plurality of electric oscillators arranged to define an imaginary surface, and being arranged in suitable geometrical configuration relatively to one another, comprising in combination a sectionalized artificial retardation line, a plurality of insulated parallel contact strips arranged to form a surface similar to that of the oscillator arrangement, respective successive strips being individually connected to corresponding successive individual sections of the artificial line, a contact carrier having a plurality of sliding contacts equal in number to that of the oscillators and forming a figure geometrically similar to that formed by the oscillators, respective contacts being connected to correspondingly positioned oscillators, and means for rotating said carrier and said strip surface relatively to one another on at least one pivotal center to slide said contacts over the surface formed by said contact strips, the area formed by said strips covering the largest circle described by said contacts.

2. An electric compensator for a plurality of electric oscillators arranged to define an imaginary surface, and being arranged in a desired geometrical configuration relatively to one another and to a common central axis, comprising in combination a sectionalized artificial retardation line, a plurality of insulated parallel contact strips arranged to form a surface similar to that of the oscillator arrangement, respective successive strips being individually connected to correspondingly successive individual sections of the artificial line, a contact carrier having a plurality of sliding contacts equal in number to that

of the oscillators and forming a figure geometrically similar to that formed by the oscillators, respective contacts being connected to correspondingly positioned oscillators, and means for rotating said carrier on at least one axis coinciding with the corresponding common central axis of the geometrical contact figure, to slide said contacts over the surface formed by said contact strips, the area formed by said strips including the area covered by the rotation of said geometrical contact figure.

3. An electric compensator for a plurality of electric oscillators in a desired geometrical arrangement relatively to one another, comprising in combination a sectionalized artificial retardation line, a plurality of insulated contact strips spaced side by side to form a plane continuous surface, said strips being insulated from one another and respective successive strips being individually connected to corresponding successive individual sections of the artificial line, a contact carrier having a plurality of sliding contacts equal in number to that of the oscillators, and forming a figure geometrically similar to that formed by the oscillators, respective contacts being connected to correspondingly positioned oscillators, said strip surface being of sufficient size to include the entire group of sliding contacts, and means for operating said carrier to rotate said contact figure over said contact strips on a pivotal center located on the strip surface so as to maintain all contacts on the surface during the rotation of said figure.

4. An electric compensator for a plurality of electric oscillators arranged to define an imaginary surface, and being arranged in suitable geometrical configuration relatively to one another, comprising in combination a plurality of sectionalized artificial retardation lines, a plurality of insulated parallel contact strips forming a surface, similar to that of the oscillator arrangement, said surface being divided in a direction substantially transversely to said strips into a number of sections equal to the number of artificial lines, respective successive contact strips of each surface section being individually connected to correspondingly successive individual sections of one of said artificial lines, a contact carrier having a plurality of sliding contacts equal in number to that of the oscillators and forming a geometrical figure geometrically similar to that formed by said oscillators, respective contacts being connected to correspondingly positioned oscillators, and means for rotating said carrier on a pivotal center located substantially symmetrically to said strip surface sections to slide said contacts over the several sections of said contact strip surface, the latter surface having a total area at least equal to the area covered by said sliding contacts.

5. An electric compensator for a plurality of electric oscillators arranged to define an imaginary surface, and being arranged in suitable geometrical configuration relatively to one another, comprising in combination a plurality of sectionalized artificial retardation lines, a plurality of insulated parallel contact strips forming a surface similar to that of the oscillator arrangement, said surface being divided in a direction substantially transversely to said strips into a number of sections equal to the number of artificial lines, respective successive contact strips of each surface section being individually connected to correspondingly successive individual sections of one of said artificial lines, a contact

carrier having a plurality of sliding contacts equal in number to that of the oscillators and forming a geometrical figure geometrically similar to that formed by said oscillators, respective contacts being connected to correspondingly positioned oscillators, and means for rotating said carrier on a pivotal center located substantially symmetrically to said strip surface sections to slide said contacts over the several sections of said contact strip surface, the dividing line forming said surface sections being arranged so that substantially the same number of sliding contacts cooperate with each surface section, said contact surface having a total area at least equal to the area covered by said sliding contacts.

6. An electric compensator for a plurality of electric oscillators arranged on a continuous surface in suitable geometrical configuration relatively to one another, comprising in combination a plurality of sectionalized artificial retardation lines, a plurality of insulated parallel contact strips forming a continuous surface similar to that of the oscillator arrangement, said surface being divided in a direction substantially transversely to said strips into a number of sections equal to the number of artificial lines, respective successive contact strips of each surface section being individually connected to correspondingly successive individual sections of one of said artificial lines, a contact carrier having a plurality of sliding contacts equal in number to that of the oscillators and forming a geometrical figure geometrically similar to that formed by said oscillators, respective contacts being connected to correspondingly positioned oscillators, and means for rotating said carrier on an axis extending through the center of the smallest circle which includes said geometrical contact figure to slide said contacts over the several sections of said contact strip surface, the latter surface having an area at least equal to the area of said smallest circle.

7. An electric compensator for a plurality of electric oscillators arranged in space on a curved area and disposed in suitable geometrical arrangement relatively to one another and to at least one common central axis, comprising in combination a sectionalized artificial retardation line, a plurality of insulated parallel contact strips arranged to form together a continuous surface similar in contour to said curved area, respective successive contact strips being individually connected to corresponding successive individual sections of said artificial line, a contact carrier having a plurality of sliding contacts equal in number to that of said oscillators and forming a geometrical figure similar to that formed by said oscillators, respective contacts being connected to correspondingly positioned oscillators, and means for rotating said carrier on at least one axis coinciding with the corresponding common central axis of said similar figure to slide said contacts over said strip contact surface, the latter surface having an area at least equal to the area covered by said rotating similar geometrical figure.

8. An electric compensator for a plurality of electric oscillators arranged to define a spherically shaped surface and in suitable geometrical relation to one another, comprising in combination a sectionalized artificial retardation line, a plurality of insulated parallel annular contact strips, arranged to form together a spherically shaped surface similar to that of the oscillator

arrangement, respective successive contact strips being individually connected to corresponding successive individual sections of said artificial line, a hollow contact carrier adapted to the configuration of and surrounding said spherically shaped strip surface and having a plurality of sliding contacts equal in number to that of the oscillators and being arranged to contact with said strip surface, said contacts forming a geometrical figure on said carrier geometrically similar to that of the oscillators and having the same relation with respect to the vertical axis of said carrier as the corresponding oscillators have to the vertical axis of the oscillator arrangement, respective contacts being connected to correspondingly positioned oscillators, means for rotating said hollow carrier on its vertical axis to move said contacts over said strip surface, and means for moving said hollow carrier over said strip sphere also on a horizontal axis through the strip sphere to vary the angle of elevation of the vertical rotary axis of said carrier with respect to the ground.

9. An arrangement for the determination of direction of wave energy in space by means of the interference method, comprising a plurality of wave energy receivers arranged in spaced relation to define an imaginary sphere, an indicator connected to all of said receivers, and an adjustable time lag means having a plurality of constituent time lag elements, and means for interposing simultaneously a suitable number of said elements between each receiver and said indicator, the values of said numbers being inversely related to the different relative positions of said receivers to the wave front, for rendering the wave energy of all receivers simultaneously effective in the indicator, irrespective of their different relative positions to the wave front.

10. An arrangement for the determination of direction of wave energy in space by means of the interference method, comprising a plurality of wave energy receivers arranged in spaced relation to define an imaginary sphere, an indicator electrically connected to all of said receivers, and an electrical adjustable time lag means having a plurality of constituent time lag elements, and means for interposing simultaneously a suitable number of said elements between each receiver and said indicator, the values of said numbers being inversely related to the different relative positions of said receivers to the wave front, for rendering the wave energy of all receivers simultaneously effective in the indicator, irrespective of their different relative positions to the wave front.

11. An arrangement for the determination of direction of wave energy in space by means of the electrical interference method, comprising a plurality of energy receivers arranged to define an imaginary sphere, an indicator electrically connected to all of said receivers, and an electrical time lag chain common to all receivers and being divided into a plurality of sections, and means for simultaneously connecting sufficient numbers of sections between the different receivers and the indicator, for rendering the wave energy of all receivers simultaneously effective in the indicator, irrespective of the relative positions of the receivers to the wave front.

12. An electrical compensator adapted to be connected to a plurality of electrical oscillators arranged in spaced relation to define an imaginary sphere, for receiving wave energy, said

compensator comprising in combination a sectionalized artificial retardation line, a plurality of insulated parallel contact strips arranged on the surface of a sphere and dividing said sphere into a plurality of zones, and being connected successively to successive individual sections of the artificial line, a spherical contact carrier surrounding said strips, and a plurality of sliding contacts mounted on said contact carrier in spaced relation, geometrically similar to said spaced spherical oscillator arrangement, each contact being connected to the oscillator corresponding to its own position, said contacts being arranged to slide over the said contact strips to connect varying numbers of line sections to said contacts at an inverse ratio to the distances of the pertaining oscillators from the wave front, to compensate for the time lag due to the different distances of said oscillators from the wave front.

13. An electrical compensator adapted to be connected to a plurality of electrical oscillators arranged in spaced relation to define an imaginary sphere, for receiving wave energy, said compensator comprising in combination a sectionalized artificial retardation line, a plurality of insulated parallel contact strips arranged on the surface of a sphere and dividing said sphere into a plurality of zones, and being connected successively to successive individual sections of the artificial line, a contact bridge of spherical form having two axes of rotation disposed at right angles to one another and being rotatable about said strip sphere on said two axes, and a plurality of sliding contacts mounted on said bridge in spaced relation geometrically similar to said spaced spherical oscillator arrangement, each contact being connected to the oscillator corresponding to its own relative position on the spherical bridge, said contacts being arranged to

slide over said strip sphere to connect varying numbers of line sections to said contacts at an inverse ratio to the distances of the pertaining oscillators from the wave front, to compensate for the time lag due to the different distances of said oscillators from the wave front.

14. In a receiving arrangement for space wave energy including a plurality of spherically spaced wave energy receivers, and a common indicator, an electrical compensator comprising an electrical time lag chain divided into a plurality of sections and a switch gear for said sections consisting of a plurality of insulated parallel contact strips arranged on a sphere to divide the latter into a plurality of zones, said strips being connected successively to successive chain sections, a hollow spherical contact bridge surrounding said strip sphere and carrying contacts arranged in spaced relation geometrically similar to said spaced spherical receiver arrangement to slide on said strip sphere, a fork surrounding said bridge and being pivoted on an equatorial axis through said strip sphere, a hollow shaft pivotally disposed in the stem of said fork and carrying said hollow contact bridge at its inner end to rotate the bridge on its polar axis, a collector on the outer end of said shaft, having a plurality of slip rings each connected through said hollow shaft with one of said bridge contacts, brushes sliding on said rings and being each connected to the receiver corresponding in geometrical position with the bridge contact to which the pertaining slip ring is connected, whereby through the rocking movements of said fork and rotary movements of said shaft varying numbers of chain sections can be connected simultaneously between the several receivers and the indicator in accordance with the distance of each receiver from the wave front.
